UNITED STATES PATENT OFFICE.

WILLIAM ERICKSEN, OF BROOKLYN, NEW YORK.

DESIGN FOR A PICTURE-FRAME.

51,855.

Specification for Design.

Patented Mar. 12, 1918.

Application filed December 8, 1917. Serial No. 206,346. Term of patent 3½ years.

To all whom it may concern:

Be it known that I, WILLIAM ERICKSEN, a subject of the King of Norway, residing at New York, borough of Brooklyn, in the county of Kings and State of New York, have invented a new, original, and ornamental Design for a Picture-Frame, of which the following is a specification, reference being had to the accompanying drawings, forming part thereof.

Figure 1 is a front elevation of the frame showing my new design; and

Fig. 2 is an edge elevation.

I claim:

The ornamental design for a picture frame as shown.

WILLIAM ERICKSEN.
